UNITED STATES PATENT OFFICE.

CHARLES M. BLACKMAN, OF NEW YORK, N. Y., ASSIGNOR TO THE S. H. WETMORE CO., OF SAME PLACE.

DESIGN FOR AN ATOMIZER OR INHALER.

SPECIFICATION forming part of Design No. 34,202, dated March 12, 1901.

Application filed January 10, 1901. Serial No. 42,805. Term of patent 14 years.

To all whom it may concern:

Be it known that I, CHARLES M. BLACKMAN, a citizen of the United States, residing at New York, in the county of Kings and State of New York, have invented and produced a new and original Design for Atomizers or Inhalers, of which the following is a specification, reference being had to the accompanying drawing, forming part thereof.

10 The drawing represents a side elevation of my design, the essential feature thereof being shown in full lines.

The tube is provided with a main intermediate bend 1 and two minor reverse bends 15 2 and 3 upon each side of the main bend 1.

4 is a flange formed on the outer end of the tube, and 5 is a secondary tube formed or secured to the inner end of the tube.

6 is the atomizer or nebulizer bulb; 7, the bottle; 8, the cap, and 9 the discharge-tip. 20

The essential feature is the atomizer-tube having the secondary tube 5 secured thereto at the inner end, both the main tube and the secondary tube being curved and parallel throughout the length of said secondary 25 tube.

What I claim as new, and desire to secure by Letters Patent, is—

The design for an atomizer or inhaler, substantially as shown and described.

CHARLES M. BLACKMAN.
